METHOD OF AND MEANS FOR FORMING COILS

George H. Erb, South Orange, N. J., assignor to
Federal Telephone and Radio Corporation,
Newark, N. J., a corporation of Delaware

Application April 24, 1943, Serial No. 484,356

5 Claims. (Cl. 153—64)

1

This invention relates to methods of and means for forming coils, and more particularly to an arrangement for forming internally wound coils.

An object of this invention is to provide novel methods of and means for forming internally wound coils.

Another object of this invention is directed to the provision of a novel collapsible, coil-forming mandrel.

A specific feature of the present invention is in the winding of a coil on the threads of a collapsible threaded mandrel, screwing this mandrel into an internally threaded coil form and depositing the coil on the mandrel into the threads of the coil form by collapsing and withdrawing the mandrel.

These and other features, capabilities and advantages of the invention will appear from subjoining detailed description of one embodiment and a modification thereof, illustrated in the accompanying drawings, in which:

Fig. 1 is a longitudinal cross-sectional view of a coil form showing the coil-forming mandrel of the present invention partially inserted;

Fig. 2 is an end view of the exposed end of the coil-forming mandrel of Fig. 1;

Fig. 3 is an end view of the other end of the coil-forming mandrel.

Fig. 4 is a partial enlarged view of the threaded portion of the coil-forming mandrel;

Fig. 5 is a partial threaded portion of a modified form of coil-forming mandrel.

In the making of internally wound coils such, for example, as an internally wound potentiometer or rheostat, in accordance with the present invention and as seen in Fig. 1, I start with an internally threaded insulated coil form 10 into which is screwed a coil-carrying, collapsible mandrel generally indicated at 12. This mandrel 12 is formed as a built-up structure comprising a central core 14 surrounded by attached segments 16 and 18, threaded for the greater part of their length and so shaped as to form about the core 14 a threaded cylindrical structure. If the segments 16 and 18 are formed of relatively rigid material for example, brass, they need be connected to the core 14 at one end only as by pairs of screws 20.

The threaded portions of the segments 16 and 18 are so designed that when these segments are properly assembled on the core 14 the threads on any one segment are aligned with the threads on adjacent segments to form a continuously threaded structure whose threads are of the same pitch as the internal threads in the coil support

2

10. According to one proposal, for example, in the potentiometer disclosed in my copending application, S. N. 484,355, filed April 24, 1943, it may be advantageous to form a double wound coil, in which case the threads on the mandrel 12 and within the coil support 10 will be double threads. Coils 22 and 24 are wound on the apices of the double threads and the ends of the coils may be held in place at one end by means of the assembling screws 20, and on the other end by means of a removable plug 26, as is more clearly shown in Fig. 3. In order that the coil wires be fitted firmly on the apices of the threads of the mandrel, as seen in Fig. 4 each thread 30 and 32 may be formed with grooves 34 and 36 respectively, into which the wires of the coils 22 and 24 will be set so that the wire of the coils, in effect, completes the threads on which they are wound.

20. A manner of actually forming the coil in accordance with the present invention will now be explained. First of all the segments 16 and 18 are assembled on the core 14 and attached thereto by means of the screws 20. The coils 22 and 24 are then wound in the grooves 34 and 36 of the threads 30 and 32 formed about the mandrel 12, the ends being tied down to the mandrel in any suitable manner as by utilizing the holding screws 20 at one end and inserting the removable plug 26 at the other end. The mandrel 12 with 30 the coils wound on it is then screwed into the coil form 10. When the mandrel 12 is screwed into its final position the screws 20 are removed, releasing the segments 16 and 18 from the core 14. The plug 26 is also withdrawn and the core 14 is 35 pulled out from among the assembled segments. For this purpose the core 14 may be made slightly longer than the segments 16 and 18, as indicated in Fig. 1, and may be provided with a through bore 37 or any suitable means with which 40 a tool for pulling out the core may be used. After the core 14 is withdrawn, the segments 16 and 18 are collapsed inwardly and carefully removed, the coils 22 and 24 on their apices automatically 45 springing out under their own resiliency into the bottom of the internal threads formed with the coil form 10. These coils 22 and 24 will stay in the bottom of these internal threads under their own spring action and the ends of the coils can be held in place in any suitable manner. On the 50 inner end of the coil form 10 a passage or passages 28 may be provided for withdrawing the inner leads of the coils if contact thereto is desired.

It is to be pointed out that while for the purposes of illustration I have described my inven-

tion in connection with a double coil utilizing a double-threaded mandrel, it will be obvious to those skilled in this art that the invention is equally applicable to a single coil utilizing a single threaded mandrel. It will also be noted that in the form of invention illustrated I have formed the outer surface of the core 14 as a hexagon surrounded by six segments, three small segments 16 and three larger segments 18. The number of segments, however, will depend upon the size of the coil to be formed and the size of the mandrel necessary, the criterion to be kept in mind being the number of segments required to permit collapse and withdrawal of the individual segments after the core 14 has been removed. Generally speaking, the greater the diameter of the mandrel and the coil to be formed, the greater the number of segments required. Likewise, the greater number of segments necessary results in a greater number of sides or bases formed on the core 14, but these need not necessarily be made plane as in the example given.

It is also possible to wind a double coil in accordance with the present invention by winding the two coils both on the apices and between the threads of a single threaded mandrel as illustrated in Fig. 5. As there illustrated, the collapsible mandrel 12' is formed of segments 16' and 18' which may be identical with the corresponding segments shown in Fig. 1 except that they are single threaded instead of double threaded. The coils 22' and 24' are wound upon both the apices and the bottoms of the single threads and, upon collapse of the mandrel within the coil form, the wires will be respectively deposited in the bottoms and on the apices of the threads of the internally threaded form. In all other respects the method and means will be the same as previously described, except that slightly greater care may be required in removing the threaded segments after withdrawal of the core.

While I have described above the principles of my invention in connection with certain particular coils, coil forms and mandrels, it is to be clearly understood that this description is made only by way of example and not as a limitation on the scope of my invention as set forth in the objects and the accompanying claims.

I claim:

1. The method of forming an internally wound coil, which includes the steps of winding the coil on the apices of the threads of a threaded collapsible mandrel, screwing the mandrel with the coil thereon into an internally threaded coil support, and then collapsing and withdrawing the mandrel, leaving the coil in the internally formed threads of the coil support.
2. The method according to claim 1, in which said threaded mandrel is formed by a central core surrounded by a plurality of aligned, threaded removably attached arcuate segments, and in which said mandrel is collapsed and withdrawn

by disengaging said segments from the central core, withdrawing the central core and then inwardly collapsing and withdrawing the individual arcuate segments.

5 3. The method according to claim 1, which includes the step of winding a second coil portion in the bottom of the threads on the collapsible mandrel and depositing this second coil portion on the apices of the internal threads of the coil 10 support upon the collapse and withdrawal of the mandrel.

4. Coil-forming apparatus including, in combination, a collapsible mandrel comprising a longitudinal central support, a plurality of arcuate segments removably fastened to said support, said 15 segments being so correlated as to form together an outer cylindrical surface and being threaded for the greater part of their length, the threads on one segment meeting the threads on the adjacent segments so as to form a complete thread over the greater part of the mandrel, the apices of the threads being formed with a wire-receiving depression, whereby a wire coil may be wound in said depression to complete the threads on the 20 threaded mandrel, and an internally threaded coil support adapted to receive the threaded mandrel, whereby, when the mandrel carrying the coil is wound into the threaded support and the mandrel is collapsed by removing the central support and the attached threaded segments, the coil seats in the bottoms of the threads in the coil support.

5 5. A collapsible coil-winding mandrel including, in combination, a longitudinally extending central support, a plurality of longitudinally extending arcuate segments removably fastened about said central support, said segments being so correlated as to form together an outer cylindrical surface, and being externally threaded for the greater part of their length, the threads on one segment meeting the threads on the adjacent segments so as to form a continuous thread over the greater part of the mandrel, the apices of the threads being formed with a wire-receiving groove in which the wire of the coil to be formed is 40 wound.
